ELECTRICAL CONNECTOR DEVICE.

APPLICATION FILED OCT. 22, 1917.

1,370,509.

Patented Mar. 8, 1921.

4 SHEETS—SHEET 4.

lower portion 119 of the cam-plunger 105 is twisted and extends through a slot in the cup-shaped portion 118 of the oscillating member 112, whereby reciprocation of the plunger 105 would cause oscillation of the oscillating member 112.

A coil-spring 120 surrounding the eyelet 117 serves to return the oscillating member 112 and the cam-plunger 105 when the insertible device is unscrewed from the screw-shell contact 83. One end 121 of this coil-spring engages the oscillating member 112, and the other end 122 of the spring is held against movement by engagement with a portion of the insulating member 123. The quick-detachable contact means 87 for the I-slot 124 comprise a strip of sheet-metal bent to form two opposed spring contact fingers 125. These contacts are secured to a conductor-plate 126 by means of a rivet 127. The conductor-plate 126 is electrically connected with the binding-terminal 89 by means of a screw 128 threaded into the conductor-plate 126, a conductor-plate 129 through which the screw 128 extends, and the screw 96 which extends through an opening in the conductor-plate 129 and is threaded into the binding-terminal 89. The screw 128 serves to hold the conductor-plates 126 and 129 in position on the insulating member 123. The screw 96 assists in holding the insulating member 123 in position on the insulating member 94.

The contact means for the T-slot 130 comprise a strip of sheet material 131 bent to form two opposed spring contact fingers, and a strip of sheet material 132 bent to form a contact finger lying in a plane substantially at right angles to the planes of the contact fingers 131, the contact fingers 131 and 132 being secured to a conducting-plate 133 by means of a rivet 134. The conducting-plate 133 is electrically connected with the binding-terminal 90 by means of a screw 135 threaded into the conductor-plate 133, a conductor-plate 136 through which the screw 135 extends, and the screw 102 which extends through the plate 136 and is threaded into the binding-terminal 90.

Clips 137 may be secured to the insulating member 94 by means of screws 138, which also extend through openings in the insulating members 94 and 123 for holding them together.

The circuit for the threaded-shell receptacle portion is from the binding-terminal 89, through the screw 96, eyelet 97, switch-contact 95, contact 114, switch-contact 91, screw 92, threaded shell 83, translating device, center contact 84, screw 99, switch-contact 98, contact 113, switch-contact 101, screw 102, eyelet 103, to the binding-terminal 90.

The circuit for the quick-detachable receptacle portion 85 is from the binding-terminal 89, through the screw 96, conduc-

tor-plate 129, screw 128, conductor-plate 126, contact fingers 125, translating device, contact fingers 131 and 132, conductor-plate 133, screw 135, conductor-plate 136, and screw 102 to the binding-terminal 90.

Both the shell contact 83 and the center contact 84 are normally dead. When, however, an insertible connector device is screwed into the threaded shell 83, the switch mechanism 88 is actuated to electrically connect the center contact 84 with the binding-terminal 90, and the shell contact 83 with the binding-terminal 89. When the insertible device is pressed inwardly on the center contact 84 the cam-plunger 105 is caused to slide in the frame 115. This reciprocation of the cam-plunger 105 causes a rotation of the member 112 due to the movement of the twisted part 119 of the cam-plunger through the slot in the member 112. As the oscillative member 112 rotates, it causes the leaf spring 110 to slide along the end of the arm 109 until the arm 109 is perpendicular to the leaf spring 110. A further movement of the oscillative member 112 causes the switch member 104 to snap, bringing the contact 113 between the contacts 98 and 101, and bringing the contact 114 between the contacts 91 and 95, thus electrically connecting both the shell and center contacts with their respective binding-terminals.

When the insertible device is unscrewed from the shell contact 83, the spring 120 rotates the member 112, which forces the cam-plunger 105 outwardly, due to the engagement of the twisted portion 119 with the member 112. As the member 112 oscillates, it causes the leaf spring 110 to slide along the end of the arm 109 until the arm 109 is perpendicular to the leaf spring 110. A further movement of the member 112 causes the switch member 104 to snap, moving the contact member 113 from between the contact members 98 and 101 and moving the contact member 114 out from between the contact members 91 and 95, thus disconnecting both the center and threaded-shell contacts from their respective binding-terminals. Due to this snap action, the contact is quickly made and broken, and the danger of arcing and burning the contacts is prevented.

We claim as new and desire to secure by Letters Patent of the United States:

1. An electric receptacle comprising center and threaded-shell contacts for engagement with the corresponding contacts of an insertible device; and a quick-break snap circuit-controller actuated by the insertion of the insertible device for controlling the receptacle circuit.

2. A connector device having a movable contact engaged and moved by the contact of a co-operating connector device, a quick-break snap circuit-controller for controlling
